GEORGE W. MEARS, OF BROOKLYN, NEW YORK.

SLIDABLE HANGER.

1,259,261.

Specification of Letters Patent. Patented Mar. 12, 1918.

Application filed May 13, 1914. Serial No. 838,191.

To all whom it may concern:

Be it known that I, GEORGE W. MEARS, a citizen of the United States, and a resident of Brooklyn, Kings county, State of New York, have invented an Improvement in Slidable Hangers, of which the following description, in connection with the accompanying drawings, is a specification, like figures on the drawings representing like parts.

The present invention relates to slidable hangers, the object being to improve and simplify the same.

I show a door hanger illustrating one embodiment of my invention in the accompanying drawings, in which,

Figure 1 is a front elevation of a door hanger of the ball bearing type showing the same fixed to the wall of a building, and supporting a sliding door in closed position;

Fig. 2 is a view partly in vertical longitudinal section of the door hanger proper;

Fig. 3 is a vertical cross section on the dotted line 3—3, Fig. 2;

Fig. 4 is a perspective detail of an end portion of the spacer, and,

Fig. 5 is a perspective detail showing tracks formed from separate strips of metal.

As indicated in Fig. 1, the door hanger illustrating an embodiment of my invention is affixed to the wall of a building, commonly to a horizontal member of the frame thereof, as a girder 1. The door 2 operating in connection with the said hanger is secured in a suitable manner to a carriage member 3 so as to depend therefrom. According to Figs. 2 and 3, said carriage member is provided at its sides with suitable, preferably channelled race-ways or bearings 4 to receive antifriction balls 5 which travel in suitable ways or tracks 6, shown in the present instance as channels formed in the depending sides 7 of an inverted U-shaped housing 8 attached directly to the girder 1 referred to.

The said housing may conveniently be formed from a single strip of metal with rounded upper corners 9 connecting a flat top portion 10 with the depending sides 7 referred to. The hanger may readily be fastened directly to the girder 1 by means

of suitably spaced bolts 36 passing through said top portion and secured by means of nuts 37. In forming the channelled tracks 6, I have flattened the outermost portions 38 or those which join the obliquely disposed elements of said tracks, to give greater strength thereto than is possible where the said elements connect at a more or less acute angle.

Although the tracks 6 are here shown as preferably embodied in a U-shaped housing, I have illustrated in Fig. 5 another form in which the depending sides are formed from separate strips 11 with suitable channels or tracks 12 upon which the antifriction balls may travel in the same manner as that described in connection with the U-shaped form of housing and channelled tracks. Where the depending sides are formed of separate strips, they may conveniently be spaced and suspended by means of connecting members 42 having suitable means, as the bolts 36 and nuts 37, for attachment to a fixed part of the building in which the slidable door is to be mounted.

To maintain the balls 5 properly spaced, I have provided a spacer 13, shown as and preferably U-shaped in cross-section and arranged in inverted position similar to the arrangement of the housing 8. This spacer 13 is provided along its depending side members with rows of properly spaced openings 14 for the several balls. To better retain said balls in said openings, I have provided at either side of each opening, a pair of concaved lips 15 and 16, Fig. 4, which embrace the respective balls and provide suitable bearings and positioning surfaces therefor. Said retaining lips are preferably cupped or concaved as shown to embrace or encompass, more or less, the balls held between them, whereby the said balls are prevented from accidentally dropping out of position when not otherwise held in their proper race-ways or tracks.

In operation, the door 2 suspended from the carriage member 3 may be moved back and forth on the tracks at any desired speed. Whatever the speed of the carriage member may be, the spacer 13 travels in the same

22

direction, but at substantially one-half that speed. It has been found in practice that, owing to friction and lack of uniformity in pressure at the various points of contact between the balls and their respective tracks, the traveling members are likely to slip relative to one another, permitting the door suspending carriage 3 to outrun the spacer 13. In such a case, upon the return run, the spacer is likely to reach the end of its run in advance of the carriage member where-as both of them should reach their normal positions simultaneously. I have found that this latter result may be substantially effected if the balls 5 are made, as herein illustrated, to contact with their respective bearings in such a manner that the line joining the two upper points of contact on each ball will preferably be horizontal and parallel with the corresponding line joining the two lower points of contact. This relative positioning of the balls with respect to their bearings is conveniently obtained by disposing the surfaces 17, 18 and 19, 20, 25 forming the bearings of the tracks, toward each other at the same angle as the surfaces 21, 22 and 23, 24 respectively, forming the bearings in the carriage member 3 (Fig. 3). Notwithstanding that the balls be arranged as hereinabove described, should the carriage member still outrun the spacer—owing to careless operation or to derangement of the parts—I have disclosed a spacer having its end formed as by closing it to prevent a stop surface, a suitable form being shown at 39, Fig. 4, so that it may again be made to register properly with the carriage member. Thus when the door is moved in the return direction, as indicated by the arrow in Fig. 2, if the spacer 13 has lost its proper relative position with respect to the carriage 3 because the former has traveled at less than its intended speed, the said carriage will contact with the stop surface 39 of the spacer, thus carrying the latter to an extreme end position, as shown in Fig. 1, thereby properly positioning both members in readiness for the next movement of the door in the opposite direction.

50 If the spacer is made, as heretofore generally the custom, of a length equal only to the width of the door, since said spacer travels but one-half the distance the door travels, when the latter reaches the end of its course, its forward end will be found to have outrun the adjacent end of the spacer and to project forward without support. This soon allows the door to sag at its said forward end and to lose its alinement with all the attendant difficulties. To obviate this, I have made the length of the spacer 13 greater than the width of the door 2, as shown in Fig. 1, the spacer there being indicated in dotted lines, so that when the door

is moved to its closed position, the forward end of its supporting carriage will engage and receive support from the additional balls carried by the spacer extension hereinabove referred to.

With this construction, however, it is clear that a substantial portion of the spacer with the balls carried thereby will overhang the carriage 3 when the door is in its extreme positions. If the door be at the right, as in Fig. 1, the spacer overhangs at the left and if the door be at the left the spacer overhangs at the right. In the construction just described, it will be obvious that the balls positioned at the ends of the spacer must be provided with means to retain them in position inasmuch as they are thus at times deprived of the support of the bearing surfaces of the carriage member. To accomplish this, I have not only provided a plurality of ball retaining lips 15 and 16 in the spacer, cupped as described, but I have also constructed the spacer in such manner as to cause its walls thereby to press the balls firmly against the tracks 6 so that when the carriage member is in such position that the balls receive support from one of the race-ways only, said balls will still be pushed into firm contact with the other race-ways, thus preventing looseness and rattle. This pressing of the balls always into contact with the outer interior bearings permits each succeeding ball without unnecessary noise and impact, to pass from one track to the next, the balls being maintained constantly in proper position. This result may conveniently be effected by spacing the free edges of the depending sides slightly farther apart than their respective upper connected edges so that in assembling the device, the sides of the spacer may be sprung to permit its being properly positioned between the depending sides of the housing. Thus the balls carried by the spacer will be pressed into firm contact with the tracks and be held constantly in proper position.

Door hangers of the construction described and illustrated herein as embodying one form of my invention have distinct advantages over the older forms, among which may be pointed out the superior strength of the inverted U-shaped housing, particularly over the type in which the upper corners are angular. It will be obvious that by joining the flat upper portion of the housing to the depending sides with a swinging curved corner, the strength of the material will be better conserved than where the corner is angular. This would be particularly true where the housing is stamped from a single piece of metal. Similar conservation of strength is effected in the track members by forming the outermost portions of the channels or outer race-ways with a mini-

mum lateral displacement of material. It will be understood that such a construction is better adapted to withstand the outward and downward thrust of the balls than 5 would be a bearing having relatively wider bearing surfaces and relatively sharper angles joining the same.

It has been pointed out that the tracks or 10 depending side members may be connected by a flat top portion, the preferred form being shown in Fig. 2 of the drawings. When thus constructed, the flat top serves both as a protective covering for the bearings underneath and as a means whereby the tracks 15 may be attached directly to a girder, as illustrated. The continuous flat top forms with the tracks a housing which effectively prevents dust and other obstructions from lodging in the ball race-ways or other working 20 parts of the hanger. Moreover, the flat top or crown piece, having a substantial width, may be bolted directly to a girder thus securing the hanger against lateral tilting. In a similar manner, the tracks, as shown in 25 Fig. 5, may be suspended from a girder by means of flat connecting top pieces conveniently spaced along the said tracks for the purpose of holding them in proper alignment as well as for securing them to a 30 girder or other suitable part of a building.

A further improvement in slidable hangers of the ball bearing type is illustrated in Fig. 2, the object being to still further promote smooth running and noiselessness of 35 operation. As pointed out heretofore, it has been found desirable to have the balls and their respective bearings fit snugly. Attention has also been called to the relative speeds of the carriage member 3 and the spacer 13 40 carrying the balls 5, it being noted that the balls and the spacer advance at one-half the speed of the carriage member so that the advancing end of the latter, in its travel, will pass from one ball to the next, performing 45 this operation as many times as there are balls mounted in the overhanging end of the spacer. Inasmuch as the carriage member carries the load, it is contemplated that the advancing end may be found to sag or 50 to tilt, in which case the forward edges of the bearing surfaces in the carriage member might strike the surface of the ball at an improper angle thus hindering smoothness of running. To obviate such a difficulty, 55 should it arise, I flare the ends of the bearing surfaces of the carriage slightly so as to form tapering approaches as 53, it being obvious that if material is cut away at these ends, the cross sectional area of the opening 60 of the raceway will be larger than that of the raceway at parts relatively away from the ends. Thus, as the end of the carriage member advances, instead of striking each succeeding ball in the manner heretofore de-

scribed, it will engage the same gradually 65 by means of the tapered opening.

While the hanger herein described and illustrated is of the kind adapted to be used with sliding doors, its use is not thus restricted, it being obvious that the invention 70 may be applied to hangers designed for other purposes such as slidable clothes racks, slidable windows, and the like.

I claim as my invention;

1. The combination of a track member and 75 a carriage member slidable relatively thereto, said members having opposed ball receiving grooves, balls in said grooves co-operating with said members in supporting one by means of the other while permitting travel 80 of one relatively to the other, a ball retaining member having a yielding ball carrying portion between said members, said portion having means for engaging the balls at one side of their axes and means to press said 85 portion, and thereby said balls, laterally toward and against the member adjacent to the other side of said axes in order to hold the balls normally in contact with the ball receiving groove and prevent injurious rattling of the balls upon the bearing surfaces 90 of said groove.

2. The combination of track members and a carriage member slidable relatively thereto, opposed ball receiving grooves in said 95 members, balls in said opposed grooves, co-operating with said members to support one by means of the other while permitting travel of one relatively to the other, a ball retaining member having a yielding ball 100 carrying portion between the carriage member and each of the track members, said portions having means for engaging the balls at one side of their diameters, and means to press each of said ball carrying portions, 105 and thereby said balls, laterally toward the track member adjacent thereto to hold the balls normally in contact with the ball receiving grooves in both track members thereby to prevent injurious rattling of the 110 balls upon the bearing surfaces of said grooves.

3. The combination of track members and a carriage member slidable relatively thereto, opposed ball receiving grooves in said 115 members, balls in said opposed grooves, co-operating with said members to support one by means of the other while permitting travel of one relatively to the other, a ball retaining member having a yielding ball 120 carrying portion between the carriage member and each of the track members, each of said portions having means for engaging the balls at one side of their diameters, whereby said balls may be pressed laterally 125 toward the track member adjacent thereto and held thereby normally in contact with the ball receiving grooves in both track

- members thereby to prevent injurious rattling of the balls upon the bearing surfaces of said grooves.
4. The combination of track members and a carriage member slideable relatively thereto, opposed ball receiving grooves in said members, balls in said opposed grooves, co-operating with said members to support one by means of the other while permitting travel of one relatively to the other, a ball retaining member having a yielding ball carrying portion between the carriage member and each of the track members, each of said portions having means for engaging the balls at one side of their diameters, and means at the end of said ball retaining member and interposed in the path of the carriage member to retain the ends of the yielding ball carrying portions in suitable spaced relation whereby the balls may be pressed laterally toward the track member adjacent thereto and held normally in contact with the ball receiving grooves in both track members to prevent injurious rattling of the balls upon the bearing surfaces of said grooves.
5. In a slideable hanger, the combination of a cross-sectionally U-shaped housing having a longitudinal channel in each side, a carriage member arranged between said channels and having inwardly converging bearing surfaces, disposed at substantially the same angle as the bearing surfaces of the longitudinal channels, balls interposed between the said channels and the said carriage member, and a spacer longer than the width of the door and having apertures for receiving said balls, said apertures being flanked with retaining lips to hold the balls in position.
6. In a slideable hanger, the combination of a cross-sectionally U-shaped housing having a longitudinal channel in each side, a carriage member arranged between said channels and having bearing surfaces co-operating with the bearing surfaces of the longitudinal channels, balls interposed between the said channels and the said carriage member, and a spacer having means for holding the balls to press the same against said longitudinal channels, and spring inwardly to maintain the balls in firm contact with the bearing surfaces of the carriage member.
7. In a slideable hanger, the combination of a housing having a longitudinal channel in each side, a carriage member arranged within said housing and having bearing surfaces co-operating with the bearing surfaces of the longitudinal channels, balls interposed between the said channels and the said carriage member, and a spacer having apertures for receiving said balls and adapted to resiliently press said balls into said channels,
- said apertures being provided with means for holding the balls in position.
8. In a slideable hanger, the combination of a housing having a longitudinal channel in each side, a carriage member arranged between said channels and having bearing surfaces co-operating with the bearing surfaces of the longitudinal channels, balls interposed between the said channels and the said carriage member, and a spacer closed at one end and having means for holding the balls, whereby the carriage member in its run in one direction contacts with the closed end of the spacer and propels the spacer and thereby compensates for any lost motion of the spacer.
9. In a slideable hanger, the combination of a pair of spaced members provided with longitudinal channels, means connecting said members to each other and to a support, a carriage arranged between said members and having inwardly converging bearing surfaces disposed at substantially the same angle as the bearing surfaces of the longitudinal channels, balls interposed between the said members and the said carriage, and a spacer having apertures for receiving said balls and adapted to resiliently press said balls into said channels, said apertures being flanked with retaining lips to hold the balls in position.
10. In a slideable hanger, the combination of a pair of spaced members provided with longitudinal channels, means for connecting and supporting said members, a carriage arranged between said members and having bearing surfaces co-operating with the bearing surfaces of the longitudinal channels, balls interposed between the said members and the said carriage and a spacer having means for holding the balls to press the same against said longitudinal channels, and resiliently tending to spring outwardly to maintain the balls in firm contact with the bearing surfaces of said channels.
11. In a slideable hanger, the combination of a pair of members provided with channels having bearing surfaces, means for supporting the members in spaced relation, a carriage arranged between said channels and having bearing surfaces co-operating with the bearing surfaces of the channels, balls interposed between the members and the carriage, and a spacer having apertures for receiving said balls and adapted to resiliently press said balls into said channels, said apertures being provided with means for holding the balls in position.
12. In a slideable hanger, the combination of a housing having a longitudinal channel in each side, a carriage member arranged between said channels and having bearing surfaces co-operating with the bearing surfaces of the longitudinal channels, balls inter-

posed between the said channels and the said carriage member, and a spacer closed at one end and adapted to resiliently press said balls into said channels and having means for holding the balls, whereby the carriage member in its run in one direction contacts with the closed end of the spacer and propels the spacer and thereby compensates for any lost motion of the spacer.

In testimony whereof, I have signed my name to this specification, in the presence of two subscribing witnesses, this 8th day of May, 1914.

GEO. W. MEARS.
